CLAIM

The ornamental design for a medical injector as shown and described.

DESCRIPTION

FIG. 1 is an upper, left, front perspective view of our new design for a medical injector.

FIG. 2 is a right elevation view thereof.

FIG. 3 is a left elevation view thereof.

FIG. 4 is a top plan view thereof.

FIG. 5 is a bottom plan view thereof.

FIG. 6 is a front elevation view thereof; and,

FIG. 7 is a rear elevation view thereof.

The broken lines shown in the figures depict portions of the medical injector that form no part of the claimed design. The dash-dot-dash lines represent boundaries on the medical injector that form no part of the claimed design.
